APPARATUS FOR PRODUCING THREADED SPANGLES

Louis Brandt, New York, N. Y., assignor to
Joseph Brandt & Bro. Inc., New York, N. Y.

Application May 15, 1941, Serial No. 393,679

2 Claims. (Cl. 223—48)

This invention relates to apparatus for producing threaded spangles, that is, threads of spangles in which the individual spangles are arranged and secured on a thread in flatwise position thereon, that is, with the opposite faces of the spangles lying against adjacent parts of said thread.

This invention is concerned primarily with a means for feeding the spangles and the string on which they are strung to the machine which arranges the spangles in said flatwise relation and which secures the spangles in said relation. However, the machine itself, which for convenience in reference will hereinafter be designated as a spangling machine is known to those skilled in this art.

For convenience in handling, spangles which are to be arranged as indicated above flatwise on a string threaded therethrough are first mounted on supply strings in adjacent face to face relation co-axially on their respective strings which are threaded through the spangle apertures, one supply string carrying say about two yards of spangles. In accordance with the present invention, the spangles are transferred from their supply strings to the string on which they are to be secured flatwise in the finished product. More particularly, pursuant to the present invention the spangles are disposed in freely movable relation on a string threaded through the apertures of said spangles, and since in the finished product the spangles are disposed flatwise on the string to which they are secured and which is threaded therethrough, the string must be of considerable length. For example, when eight yards of spangles are disposed on the supply strings in co-axial relation adjacent to each other, in the finished product wherein the spangles are disposed flatwise, the length of the string must be about 160 yards for spangles which are about $\frac{1}{16}$ of an inch in diameter, presupposing the normal flatwise disposition of the strings with the faces of adjacent spangles in slightly overlapped relation, as they usually are in the finished product. It will be understood that this long string must be passed through the apertures in the spangles and fed into the spangling machine together with the spangles at the proper speed. By the present invention provision is made for feeding the string and the spangles through which the string is threaded to the spangling machine in a greatly improved and advantageous manner. This constitutes one of the objects of the present invention.

In feeding the spangles to the spangling ma-

chine, a number of spangles are positioned adjacent the intake of the machine in position to be moved by gravity into the machine. If too many spangles are disposed at the intake of the machine, the weight of said spangles interferes with the proper operation of the machine and the resulting product is frequently defective. This objection and disadvantage is eliminated in accordance with the present invention by providing means for limiting the number of spangles adjacent the intake of the machine.

The above and other objects of the machine will best and more fully be understood from the following description considered with reference to the accompanying drawings.

In the drawings:

Fig. 1 is a side view of the spangle and thread feeding apparatus, associated with a spangling machine which is shown more or less diagrammatically;

Fig. 2 is a side view on a larger scale of part of the spangle and string feeding apparatus;

Fig. 3 is a view on a larger scale on the line 3—3 of Fig. 1 showing a part of the spangle-feeding apparatus;

Fig. 4 is a view similar to Fig. 3 taken on the line 4—4 of Fig. 2;

Fig. 5 is a top plan view of the apparatus illustrated in Fig. 1;

Fig. 6 is a view in elevation of the rear part of the apparatus;

Fig. 7 is a view of a multiplicity of spangles disposed in adjacent and co-axial relation on a string;

Fig. 8 is a view of a length of the finished product at one side thereof, showing the spangles disposed and secured flatwise on the string;

Fig. 9 is a view of the other side of the string of spangles shown in Fig. 8.

Referring now to the drawings in detail, a multiplicity of the spangles 10 are arranged co-axially on part of a string 12 in freely movable relation thereon, said string being threaded through the apertures of said spangles. Said string is of great length compared to the combined thickness of all of the spangles through which said string is threaded and is, therefore, for convenience wound on a spool 14 as shown in Figs. 1, 5 and 6, said string forming part of the spangle-feeding apparatus illustrated in said figures of the drawings and also in Figs. 2, 3 and 4. It will be understood that the spangles are initially furnished on supply strings, in lengths of say about two yards of spangles, and that said spangles are transferred to mounting string

12 by attaching the end of the latter to the supply string for drawing said string 12 through the spangles, after which all of the supply strings are removed. It will be understood, further, that string 12 is continuous and free from knots. Said apparatus for and the method of feeding the spangles 10 and string 12 to the spangling machine 16 will now be described.

Spool 14 is mounted for rotation on a spindle 18 and the string 12 wound on said spool extends over guide rollers 20 and 22, said spool and said guide rollers, particularly guide roller 22, being mounted in elevated position above the intake 19 of the spangling machine, the arrangement being such that string 12 slopes downwardly from said elevated position thereof to the intake of said machine. String 12 is drawn through the machine at the proper speed by the take-up roll 24 on which the finished string of spangles is wound, said take-up roll being driven by a pulley 26 in timed relation to the operation of the machine. Spool 14 is provided with a braking device and for that purpose has a grooved section 28 in fixed relation therewith which is engaged by a tensioned cord 30. One end of said cord is fixed to the standard 32, as indicated at 34, and the other end of said cord is fixed to one end 36 of a metal link 38, the opposite end 40 of which is pivotally secured to support 35. End 36 of link 38 is connected to a weighted roller 42 which is supported on thread 12, the weight for said roller being indicated at 44. Additional weights 46 and 48 are connected to the end of link 38 and at a point intermediate said ends. The devices just described provide convenient means for tensioning string 12 and for preventing the free rotation of spool 14 on the spindle, but any other suitable string tensioning arrangement can be used instead.

The spangles 10 disposed on string 12 move downwardly thereon over a downwardly inclined guide and support 50 mounted on vertical supports 52 and 54. Said guide and support 50 is as here shown in the form of a trough having opposite side walls 56 and a bottom 58. Side walls 56 constitute guides for string 12 and bottom 58 serves to support the spangles carried by said string. The spangles thus move toward the spangling machine partly by gravity and partly by the string on which they are carried, the movement of said spangles being retarded by the frictional engagement of the upper surface of the bottom 58 of the chute with the spangles. A roller 60 is positioned near the lower end of guide 50 and is rotated by a pulley 62 for assisting the movement of the spangles at the lower end of said guide. String 12 and the spangles 10 thereon also pass over a roller 64 driven by a pulley 66. From roller 64 the spangles 10 and the thread 12 pass to the inclined guide chute 68 of the spangling machine 16 and from said guide to the intake 19 of the machine.

As stated above, one of the objects and features of the invention is to prevent the accumulation of spangles on guides 68 in such numbers that the weight of the spangles would interfere with the operation of the machine. For this purpose provision is made for automatically interrupting the movement of spangles on thread 12 to supply guide chute 68 of the spangling machine. The means provided for accomplishing this result includes a barrier 70 disposed at the lower end of guide 50 adjacent roller 64. As here shown said barrier 70 is in the form of a forked member which is positioned so that the crotch 72 thereof

engages the spangles on string 12 and prevents movement of said spangles to guide chute 68 of the machine. It will be noted, however, that barrier 70 does not prevent movement of string 12 and that consequently the latter moves continuously so long as take-up roll 24 is rotated by the machine. The barrier 70 is intermittently rendered ineffective to prevent movement of the spangles to guide chute 68. For this purpose roller 64 is provided with a member 74 fixed to said roller in position spaced radially from the hub 76 thereof. During each revolution of roller 64 member 74 engages string 12 and raises said string above hub 76 of the roller to an elevated position such that the spangles slide down the string over and past the crotch of barrier 70 to the guide chute 68 of the machine. Thus groups of spangles 10 are supplied intermittently to guide chute 68 of the spangling machine and the arrangement is such that the number of spangles on the guide chute 68 at any one time is insufficient to interfere with the operation of the machine. Fig. 2 shows the position of roller 64 and more particularly member 74 thereof for elevating the string 12 so that the barrier is rendered ineffective to prevent movement of spangles toward the guide chute 68, and this position of the roller is also illustrated in Fig. 4. When, as illustrated in Figs. 1 and 3 the string 12 and the spangles 10 carried thereby rest on the hub 76 of roller 64, barrier 70 prevents movement of the spangles to the guide chute but, as stated, permits the string to pass freely over the crotch of the barrier to the spangling machine.

It will be observed that roller 64 is driven in timed relation to the operation of the machine and for that purpose the pulley 66 of said roller is connected by a belt 78 to a pulley which is driven by the shaft which rotates roller 60 and which is driven by pulley 62. A belt 80 connects pulley 62 to a driving pulley 82 which is fixed to and rotated by a shaft 84. Said shaft is driven by the main shaft 86 of the spangling machine and is connected by a belt 88 to the driving pulley 26 of the shaft which rotates take-up roll 24.

As stated above, the spangling machine 16 is of known construction and operation and therefore requires no detailed description. It will be understood also that said machine is supplied with strings of thread which secure the spangles in flatwise position on string 12 which is threaded through the apertures in said spangles. Thus, as here shown, there are three supply spools 90, 92 and 94 which supply thread to the spangling machine, the threads 92a and 94a from spools 92 and 94, respectively, being twisted in opposite directions about the thread 90a which is supplied from spool 90 and about the thread 12 which is threaded through the apertures of the spangles. Thread 90a is thicker than threads 12 and threads 92a and 94a and is disposed with said last mentioned two threads as illustrated in Fig. 9 on one side of the string of spangles, the other side of the string of spangles having, as illustrated in Fig. 8, only thread 12 disposed thereon.

Thus, it is seen that the apparatus of the present invention is well adapted to accomplish the several objects thereof. It will be understood that the downward slope of the string on which the spangles are carried to the spangling machine can be varied and likewise the distance from the elevated point at the guide roller 22 to the intake of the machine may be varied. In apparatus which is now operating commercially

pursuant to the present invention, the distance from roller 22 to the intake of the machine is about 34 feet, said roller is at a height of about 7 feet, roller 64 and barrier 70 are about 3 feet below roller 22 and about 2 feet higher than the intake 19 of the spangling machine and at a distance of about 2 feet laterally of said intake. It will be understood, however, that these dimensions, while preferred, have not been established as critical and are not to be considered as limitative but only illustrative of the best mode of which I am now aware for practicing my invention.

Accordingly, while I have disclosed the presently preferred embodiment of my invention, it will be understood that the invention may be embodied otherwise than as herein specifically shown or described and that changes may be made in the various parts of the apparatus and in the arrangement thereof. Therefore, I do not wish to be limited to the embodiment of the invention here shown or to the specific construction herein disclosed as embodiments of said invention except to the extent which may be required by the scope of the appended claims.

Having thus described my invention, what I claim and desire to secure by Letters Patent is:

1. Apparatus for feeding spangles to a machine by which the spangles are arranged and secured substantially in flatwise position on a string which is threaded through said spangles, said apparatus comprising means for supporting said spangles and for effecting movement thereof to said machine, means mounting said string for the movement thereof into said machine simultaneously with the movement of the spangles to the machine, a barrier between said machine and some

of the spangles on said string for preventing the movement of spangles to said machine, and a rotary member having an eccentric part operable to engage said string intermittently and to raise the latter intermittently in relation to said barrier for rendering said barrier ineffective to prevent movement of spangles to the machine.

2. In apparatus for feeding spangles to a machine for arranging and securing apertured spangles substantially in flatwise position on a string threaded through said spangles, said apparatus comprising a supply spool for said string, means for mounting said spool for rotation, means for guiding said string for movement to said machine in such manner that the string supplied from said spool slopes downwardly to said machine from an elevated point spaced therefrom and the spangles move downwardly on said string toward said machine, said machine being provided with guide means to support a plurality of said spangles adjacent spangling elements of said machine, means positioned between said guide means of the machine and said elevated point at a lower elevation than the latter for controlling the movement of spangles on said string to said guide means of the machine, said last mentioned means comprising a forked member through which the string passes to the machine, said forked member having a part normally in the path of movement of the spangles on said string to said guide means, and means comprising a rotary member having an eccentric part intermittently engageable with said string for intermittently raising the latter above said part of the forked member whereby the spangles can move downwardly on said string past said part.

LOUIS BRANDT
